UNITED STATES PATENT OFFICE

BERNHARD LANDAU, OF COLLEGE POINT, NEW YORK

VENTILATOR CONSTRUCTION

Application filed December 5, 1928. Serial No. 323,826.

This invention relates to ventilator construction; more particularly to metallic ventilators for framed members, such as doors, windows, skylights, or the like.

5 My invention is more particularly directed to the provision of a ventilator, whether used in conjunction with doors, windows or skylights, which functions efficiently as a ventilator to permit the ready circulation of air, 10 to give the privacy of opaque members and at the same time provide efficient fireproof construction. Still more particularly, this invention is directed to the provision of all metal construction ventilators for doors, 15 windows or the like, which may be used for interior work and be ornamented, such as by painting or otherwise coating with rust-proofing material, the structure being so formed that each of the components, such as 20 the louver members, may be rust-proofed, painted or otherwise treated, before assembly, without detracting from the ornamental appearance or in any way deterring from the effectiveness of the assembly.

25 It is an object, therefore, of my invention to provide a ventilator for doors, windows and the like which includes louver members, each of which is individually formed and assembled in multiple units, as desired, to 30 constitute a ventilating area of any predetermined size.

It is still further an object of my invention 35 to provide a ventilator construction, suitable for use with a framed member, such as a door or window, the ventilator including individually formed louver members which are assembled in nested or stacked relationship relatively to the stiles and rails of a frame member, the louver members being so 40 formed as to be held in engagement with each other and the stiles and rails, particularly when these members are made of metal, without employing solder, rivets or other connections.

45 It is a still further object of my invention to provide in a ventilator construction louver members in the nature of hollow metal units which may be maintained in nested or stacked relationship to provide air circulation 50 spaces therebetween, the units being

formed with inclined air deflecting surfaces to assure proper circulation of air and depending aprons to prevent direct view through the portions forming the spaces between adjacent units, the units being so 55 formed that they may be maintained in engaging relationship to each other without necessity for employing soldering connections. It is contemplated by my invention to provide in a ventilator, louver members 60 which will have all the requisite rigidity incident to being formed as part of a door or window, extreme lightness of weight, characterized by forming the louver members of sheet metal, bent into hollow units including angularly disposed air deflecting surfaces, having downwardly disposed space 65 guarding aprons, the members being so formed whereby they may be arranged in nested relationship and maintained spaced 70 without employing soldering connections to hold the members in position whereby a fireproof ventilator may be provided, including elements which may be decorated or rust-proofed before assembly into the composite 75 structure. Still further objects of my invention reside in the provision of a ventilator which may be associated with a frame construction, such as the stiles and rails of a door or window, the ventilator including 80 louver members formed of hollow, metallic units, formed of bent sheet metal, including portions thereof formed to permit nesting or stacking in spaced relationship without the necessity of employing soldering connections, the stacked units including members 85 which are formed so as to engage the stile or rail of the frame which is part of the door or window.

Other objects of my invention include the 90 provision of a ventilator which is fire proof, rigid, inexpensive to manufacture and easy to assemble.

To attain these objects and such further objects as may appear herein or be herein- 95 after pointed out, I make reference to the accompanying drawing forming a part hereof, in which—

Figure 1 is a frontal view of a door embodying my invention;

Figure 2 is an enlarged view taken on a line 2—2 of Figure 1;

Figure 3 is a section taken on a line 3—3 of Figure 2;

5 Figure 4 is a perspective view showing the elements of my device partially assembled;

Figure 5 is a perspective view of a detail.

Making reference to the drawing, I have 10 illustrated my invention as applied to a door 10, whose upper panel 11 is provided with the ventilator 12 embodying my invention. This comprises a plurality of stacked louver members 13, disposed between the stiles 14 and the rails 15 defining the framed upper 15 panel of the door.

I prefer to make my louver members of units, each comprising hollow members, preferably formed of bent sheet metal. In the construction shown, intermediate louver 20 members 13a are preferably formed from a single sheet of metal into hollow units generally triangular in cross section. The sheet metal forming the blank is preferably first bent along the fold line 16 to provide spaced 25 side walls 17 and 18, thereby providing an internal ridge. The metal is then outwardly bent along the corners 19—19 at substantially right angles to the ridge, thus forming the arms 20 as the base of the triangular section 30 unit previously referred to. The metal is then bent downwardly along the corners 21 and then reflexively bent upwardly along the edge 22 to provide the aprons 23. The remainder of the metal of the blank is then 35 angularly bent to form the deflecting surfaces 24. The metal is then upwardly vertically bent at the apex 25 to provide the tips 26 and 27, joinder being effected by the excess portion 28 which forms the lip and 40 which is crimped into engagement over the tip 26. The crimped portion 28 is bent over the tip 26 for only a portion of its length, to leave the tips 26 and 27 uncovered, thereby 45 providing open-ended members for purposes which will appear as this description proceeds.

The members above described are arranged to be disposed in nested or stacked relation, with the apex of one member adjacent a base 50 of another immediately above it, in numbers as described.

For maintaining the members so stacked in spaced relationship, I provide a riding post 55 extending from the apex of one unit to a point adjacent the base of the next unit immediately above the same. It is preferred that this riding post be constructed of a metallic strip, as shown in detail in Figure 5, comprising an enlarged louver engaging portion 30 generally triangular in shape and an extended apex 31. These members are conveniently formed by bending a strip of sheet metal reflexively upon the fold 32, to form branches 33—33. The strip is then bent 60 angularly outwardly at 34, 34 and then in-

wardly again at 35 to provide the spaced base members 36.

A strip so formed may be inserted into each end of a louver member to dispose the extension 31 between the tips 26, 27 and to rest 70 the base members 36, 36 upon the base portions 20, 20 of the louver unit, with the spaced ends 36 to either side of the centering ridge below the fold 16 previously described. Louver units so assembled, with a riding 75 post at each end may be stacked in numbers as described, with the extension 31 fitting within the centering ridge 16, thus providing spaced portions 37 between each of the louver units. It will be observed that stacked units, 80 as described, may be held rigidly disposed within the rabbeted portion of the stiles and rails of the door. It is preferred, however, particularly where an entire metal structure is provided, to maintain the louver units in stacked relation by end channel members 38. For this purpose the channel members 38 are made of a size to frictionally engage the louver units at the aprons 23 and it is preferred that the lowermost unit be fixedly connected with the channel 38 and for this purpose, orifices 39 are provided in alignment with similar orifices on the lowermost louver unit, through which there is passed rivets 40. These channel members, it will be understood, 85 are provided to each end of the louver units to completely encase the open-ended hollow members. For completely assembling the stacked units and attach the same to the upper rail 15, it is preferred that the uppermost louver unit 13' be formed with an upwardly directed channel 25'. This is preferably formed by extending the metal from the deflecting surface 24 to provide upwardly directed flanges 26' and 27', the channel being 90 completed by the beaded, reflexively folded flanges 28'. The channel so formed on the uppermost louver member 13' serves to centrally space the louver member within the channel 38, previously described and may, 95 at the point where it engages the channel 38, be provided with orifices 41 in alignment with similar orifices 39' upon the upper portion of the channel 38, through which may be passed rivets 42 to permanently assemble the 100 louver units and channel.

It will thus be observed that I have provided a novel ventilator of extreme lightness of weight, even when made of metal and with the parts so constructed that they may 105 be assembled in spaced relationship without solder connections. It will be further observed that as I avoid the use of any solder connections between the louver units and the channel holding the same in assembled relationship, that I may ornament or rust proof these members before assembling the same, without any danger of marring the coated 110 surface.

It will be further observed that the assem- 115

bly as provided may be affixed in position without danger of separating the joints and the assembly may therefore be hammered into position.

5 It will also be observed that by arranging the members in stacked relationship, as described, the overlapping aprons, enveloping the lower constricted portion of a louver unit immediately thereunder, there is provided a ventilating surface which will be free from any objectionable draft creating openings. Similarly, the assembly as provided may be used in positions where one side of the ventilator is to be exposed to the 10 weather and the ventilator will adequately serve its intended function without ingress of rain or the like.

It will further be observed that by the simple connection between louver units and the 20 simplicity in design thereof, the ventilator space may be built of any desired length and width, without special tooling, further effecting economy in that the units may be maintained in stock and assembled within a 25 fairly wide range of tolerance.

It will be further observed that due to the similarity in construction on both side faces thereof, the units may be assembled in the door without regard to the position of the 20 unit, the appearance being the same on opposite sides of the door construction.

Having thus described my invention and illustrated its use, what I claim as new and desire to secure by Letters Patent, is—

25 1. In a framed construction, such as a door or the like, a ventilator comprising individually formed louver members, means for maintaining the same in spaced relation to provide ventilating spaces and side members frictionally engaging said louvers for holding a plurality of such louver members in the said spaced relationship.

2. In a framed construction, such as a door or the like, a ventilator comprising individually formed louver members, means for holding said louver members in spaced relation comprising spacing posts separable from said members and means on said members for holding said posts in desired relation thereto.

3. A ventilator unit for a framed construction, such as a door or the like, comprising individually formed louver members, means for holding said louver members in nested 55 relation with free spaces therebetween comprising an extension on one side and an engaging portion on the opposite side, and means for maintaining said members against displacement in said nested relation comprising side channel members.

4. In a framed construction, such as a door or the like, a ventilator comprising individually formed, hollow sheet metal louvers, portions of which are shaped to provide angularly disposed deflecting surfaces,

a spacer member for providing the ventilating spaces between louvers, each of said louvers being formed on one side to engage said spacer member and means on the other side for positioning said spacer member.

5. In a framed construction, such as a door or the like, a ventilator comprising individually formed, hollow sheet metal louvers, portions of which are shaped to provide angularly disposed deflecting surfaces, a spacer member for providing the ventilating spaces between louvers, each of said louvers being formed on one side to engage said spacer member and means on the other side for positioning said spacer member, and apron members disposed from said deflecting surface for shielding the spaces between louver members.

6. In a framed construction, such as a door or the like, a ventilator arranged to 85 include a plurality of louver members, in spaced relationship, each member comprising hollow metal units, generally triangular in cross section, formed with angularly disposed deflecting surfaces and downwardly disposed space shielding aprons, spacer members for said units, said units being formed on one side to engage said spacer members and on the other side to hold said spacing units.

7. In a construction of the character described, a ventilator comprising a plurality of individually formed louver members in stacked relation, side members engaging ends of said louver members to hold said louver members against displacement in said stacked relation, said louver members being formed at one side to engage said side members and at the other side with means to prevent displacement of said louver members from said stack and said side members.

8. In a construction of the character described, a ventilator comprising a plurality of individually formed louver members in stacked relation, and side members engaging 110 the ends of said louver members to hold said louver members against displacement in said stacked relation, said louver and side members including surfaces in frictional engagement for holding the louver members in desired relation to said side members.

9. In a construction of the character described including a plurality of louver members and side members for maintaining the same in spaced relationship, each louver member comprising hollow, sheet metal units, formed generally triangularly in cross section, with the base portions provided with space shielding, deflecting aprons and the apices with spacer member holding portions.

10. In a construction of the character described including a plurality of louver members and side members for maintaining the same in spaced relationship, each louver member comprising hollow, sheet metal units,

formed generally triangularly in cross section, with the base portions provided with space shielding deflecting aprons and the apices with spacer member holding portions and means adjacent said base portions for engaging a spacer member.

11. In a framed construction, such as a door or the like, a ventilator comprising individually formed hollow, sheet metal louver members, arranged to be disposed in nested relation, said louver members being generally triangular in cross section and having downwardly disposed space shielding aprons, a riding post formed to be retained within said hollow members and having an extension disposed through the apices of said members and arranged to engage a louver member disposed immediately above the same against displacement and channel members engaging said louver members at the base portions previously mentioned to hold the same against lateral displacement.

12. In a framed construction, such as a door or the like, a ventilator comprising individually formed hollow, sheet metal louvers, spacer members for said louvers and side channel members frictionally engaging the ends of said louver members and maintaining the same in stacked relation and fastening means for holding louver members at opposite ends of the stack against displacement.

13. In a construction of the character described, including hollow, sheet metal louver members generally triangular in shape, means for maintaining said louver members in spaced relationship to provide air circulating spaces therebetween, spacer members therefore formed of sheet metal strips arranged to be inserted in the ends of said louvers and including extensions adapted to engage the base portions of a louver member immediately thereover, to hold said louver members in said predetermined, spaced relationship and against displacement.

Signed at College Point, in the county of Queens and State of New York this 16th day of November A. D. 1928.

BERNHARD LANDAU.
